UNITED STATES PATENT OFFICE.

JOHN HERBERT KJELLSTROM, OF ROCKFORD, ILLINOIS, ASSIGNOR TO J. L. CLARK MANUFACTURING CO., OF ROCKFORD, ILLINOIS, A CORPORATION OF ILLINOIS.

FACE-POWDER CONTAINER.

Application filed July 27, 1925. Serial No. 46,219.

My invention relates to improvements in containers for carrying a supply of face powder.

Loose or pulverized face powder is the preferable form to use in vanity cases since it can be more easily applied than compacted or caked powder which is now commonly used. But, owing to its finely divided character, loose powder, as ordinarily dispensed, is apt to be spilled or dusted from its container, and a considerable portion is likely to be wasted.

The primary object of this invention is to provide a container for loose face powder which can be manufactured at a very low cost and which overcomes the disadvantages mentioned above.

Another object is to provide a loose powder container of new and improved construction having a novel means for dispensing the powder in quantities as desired by the user.

In carrying out these objects I provide a face powder container having two parts arranged in telescoping relation so that by a combined axial and rotary movement between the parts, powder will be compressed within the container and a portion of it squeezed through perforations in one of the parts.

Further objects and advantages will become apparent from the following detailed description taken in connection with the accompanying drawings in which:

Figure 1 is a vertical sectional view of a powder container embodying the features of my invention.

Fig. 2 is a side view of one of the parts of the container.

Fig. 3 is a plan view of the part shown in Fig. 2.

Fig. 4 is a vertical sectional view of a modified form of the invention.

While I have shown in the drawings and will describe in detail the preferred embodiments of the invention, it is to be understood that I do not intend thereby to be limited to the particular forms disclosed but aim in the appended claim to cover all modifications and alternative constructions falling within the spirit and scope of the invention:

Referring to the exemplary forms of the invention illustrated in the drawings, 10 55 designates a two-part container formed of

sheet metal or other suitable material. One of the parts of the container comprises an outer casing 11 which is adapted to contain a quantity of face powder. In the present instance, this casing is circular in form and 60 has a peripheral side wall 12. 13 is a beaded portion of the side wall 12 by means of which the casing may be grasped and held by one hand of the user.

Positioned within the outer casing 11 is an inner casing or closure member 14 constituting the other part of the container and co-operating with the outer casing to form the powder compartment. The member 14 has a peripheral side wall 15 which telescopes with 70 the wall 12 of the casing 11. To provide a tight slip joint between the walls 12 and 15 and at the same time reduce sliding friction between them, the wall 12 may be formed with a suitable inturned flange 16 as shown 75 in Fig. 1. The two casings may be joined in various other ways such as the one shown in Fig. 4, wherein the wall 15 fits snugly within the wall 12. Thus, it will be observed that the two casings which form the powder compartment are adapted to be manually pressed 80 together and also rotated relatively.

The top wall 19 of the inner casing 14 is preferably depressed inwardly to form a concave surface on which powder will be retained and from which powder can be conveniently removed by means of a suitable pad or puff 20. A plurality of perforations 21 are formed in the top wall through which powder may be fed from the powder compartment. In Fig. 1, 22 indicates a rounded flange having an outer knurled surface by means of which the inner casing 14 can be grasped when it is to be moved relative to the outer casing.

In operation, the outer casing is held in one hand and the inner casing in the other hand by which it is rotated and pressed inwardly. The axial movement of the two parts will decrease the volume of the powder 100 compartment, thereby causing the powder to be compressed. Upon rotation of the two parts the powder under compression will be squeezed through the perforations 21 onto the concave surface of the top wall 19 from 105 which it can be removed by the puff 20. Powder under compression in the compartment may also be forced through the perforations by merely tapping the top wall 19.

To refill the containers shown herein, the 110

two casings 11 and 14 are first separated, and then the outer one is filled with powder.

To hold the puff 20 against the outer surface of the top wall 19 and thereby prevent the powder from sifting through the perforations 21 when the container is not in use, a suitable removable cover 23 is provided. This cover has a peripheral wall 24 which is adapted to telescope with the outer casing 11. The cover serves to hold the parts of the container together.

It will be apparent that I have provided a loose powder vanity case which is extremely simple and inexpensive in construction, which is easy to operate, and which presents a neat and artistic appearance.

I claim as my invention:

A powder container having, in combina-

tion, a casing having a peripheral side wall and a closed end, a closure member comprising a perforated end wall and a peripheral side wall depending from said end wall and projecting into the side wall of said casing in telescoping relation to form a powder compartment of variable volume, the volume of said casing being substantially greater than the volume of said closure member whereby powder contained in said casing can be compressed and forced through said perforated wall by combined axial and rotary movement between said casing and the closure member.

In testimony whereof, I have hereunto affixed my signature.

JOHN HERBERT KJELLSTROM.
